ATTORNEY

UNITED STATES PATENT OFFICE.

JOSEPH HEWITT, OF ALLEGHENY, PENNSYLVANIA.

MANTEL.

SPECIFICATION forming part of Letters Patent No. 321,723, dated July 7, 1885.

Application filed October 14, 1884. (No model.)

To all whom it may concern:

Be it known that I, JOSEPH HEWITT, a citizen of the United States, residing at Allegheny, in the county of Allegheny and State of Pennsylvania, have invented certain new and useful Improvements in Mantels, of which the following is a full, clear, and exact description.

The invention will first be described in connection with the drawings, and then pointed out in the claim.

In the accompanying drawings, Figure 1 represents a front elevation of my improvement; Fig. 2, a side elevation of same; Fig. 3, a detail of one of the blocks, showing a molded back; Fig. 4, an edge view of same, showing a metallic or like backing.

Similar letters of reference indicate corresponding parts throughout the different views.

15 The mantel is preferably composed of a number of blocks, whose edges are reduced in such manner as to be conveniently mortised together.

Those portions of the mantel which are ordinarily in relief are molded, while the plane surfaces may, if preferred, be formed of plate-glass.

20 A represents a mantel composed of a number of sections or blocks of glass united by proper mortise-joints, *a*. Cast integral with and extending from the back of said pieces are lugs *B*, by means of which the mantel is cemented or otherwise secured to the chimney-breast. These lugs may be constructed 25 of glass or, if preferred, of iron. In the latter case the glass would be molded upon the lug.

The top *C* of the mantel is smooth upon the top and edges; but I mold it rough, corrugated, or figured upon the bottom, and apply thereto a backing or coating of metal, paint, or other substance. This figured and opaque back, when viewed through the medium of the transparent glass, gives the latter the appearance of being in relief, and produces an extremely agreeable effect.

40 45 The pilasters *D* may be formed in a similar manner to the top.

The moldings or relief portions of the mantel may be constructed with hollow backs, 50 the latter figured and provided with a coating, as before described.

I am aware that mantels and other articles have been made of glass for more than thirty years; also, that blocks of glass have been 55 molded, and at the same time colored in imitation of marble or other design, and then cemented within panel-frames of an ornamental form; also, that the blocks of glass have been painted and vitrified after being molded into 60 shape; but

What I consider to be new, and desire to protect by Letters Patent, is—

A mantel having its glass sections transparent, and provided on the rear thereof with 65 figures or designs visible in relief through the glass, substantially as shown and described.

JOSEPH HEWITT.
